UNITED STATES PATENT OFFICE.

WILLIAM B. MURRAY, OF PHILADELPHIA, PENNSYLVANIA, ASSIGNOR OF ONE-HALF TO CALVIN DETRICK, OF SAME PLACE.

VAULT FOR UNDERGROUND CONDUITS.

SPECIFICATION forming part of Letters Patent No. 257,743, dated May 9, 1882.

Application filed January 19, 1882. (No model.)

To all whom it may concern:

Be it known that I, WILLIAM B. MURRAY, a citizen of the United States, residing in Philadelphia, Pennsylvania, have invented certain Improvements in Vaults for Underground Conduits, of which the following is a specification.

My invention relates to an improvement in man-hole entrances and covers for vaults or testing-chambers, communicating with underground ducts for telegraph wires and cables; and the object of my invention, which is fully described hereinafter, is to effectually prevent the entrance of water into the vault.

In the accompanying drawings, Figure 1 is a vertical section of part of the roof of a vault or testing-chamber illustrating my improvements; Fig. 2, a sectional plan on the line 1 2; and Fig. 3, a sectional view, showing a modification of my invention.

In Figs. 1 and 2, A represents part of the arched roof of an underground vault or testing-chamber, with which the subterranean ducts for telegraph-wires communicate. From the paved surface *x* of the street, and through the roof of the vault, extends a casing, B, preferably of cylindrical form, and on an internal ledge, *m*, in the upper end of the casing fits a cover, D, which may be hinged at *y*', and which should be made of plate or malleable iron, in order that it may resist the shocks to which it must be subjected by passing vehicles. To prevent the bending and distortion of the cover it bears on a grating, E, of cast-iron, which rests on a flange or lugs, *t*, in the casing. At a short distance below the grate E there is within the casing and projecting therefrom a flange, G, the upturned portion *d* of which is in the present instance made of the tapering form shown, an annular receptacle, *y*, referred to hereinafter, being thus formed between the said flange and grating.

A cover, H, shaped like an inverted dish, has a flange, *e*, corresponding, or nearly so, with the tapering portion of the flange G of the casing, and between the two flanges is interposed a packing-ring, *i*, of rubber or other equivalent material, so as to make a perfectly water-tight joint. A bar, F, extends across the cover and serves to depress it and keep it down, one end of the bar fitting into a recess in one side of the casing and the other end, which is slotted, fitting over a staple, which is secured to the opposite side of the

casing, and which receives the shackle of a 55 padlock, for it is important that none but authorized parties should have access to the vault.

The outer cover, D, which may fit accurately enough in the first instance, soon becomes loose 60 enough to permit the entrance of water into the casing B; hence the importance of having a perfectly-tight joint within the casing for preventing water from dropping onto the telegraph wires or cables which pass through the 65 vault.

An attempt has been made to render the man-hole of a vault of the class to which my invention relates water-proof by placing on a ledge within a casting which does not extend 70 through the roof a simple plate without any appliances for depressing and keeping it down—a plan which has failed to exclude water from the vault. Practice has determined the fact that to make the joint tight there must be appliances for forcing down the cover. It is not essential, however, that the bar F should be used as a means for holding down the cover. There may be, for instance, a bar, F', Fig. 3, 75 provided with a screw, *m'*, for bearing on the cover, and the head of this screw may be so constructed that it will require an instrument of peculiar construction in the possession of an authorized person to operate it.

I prefer in all cases to make the flange G of 85 the upturned character shown, so that it will form the receptacle *y*, previously referred to.

Prior to removing the cover H it is not necessary to take pains to remove all the water lodged in the casing. A portion of the water 90 may remain in the receptacle *y*, for it cannot find its way therefrom into the vault.

I claim as my invention—

The combination of the vault A, the casing B, cover D, and support for the same, upturned flange G, forming a receptacle, *y*, cover H, the flange and cover being constructed substantially as described, whereby a packing-ring may be interposed between the two, and a device for keeping the said cover H down 100 to its place, all substantially as set forth.

In testimony whereof I have signed my name to this specification in the presence of two subscribing witnesses.

WM. B. MURRAY.
